ELECTRICAL MANICURING APPARATUS

Wilhelmus Gerardus Elisabeth Janssens, Drachten, Netherlands, assignor to U.S. Philips Corporation, New York, N.Y.

Filed Feb. 22, 1972, Ser. No. 228,433

Claims priority, application Netherlands Aug. 30, 1971

Term of patent 14 years

Int. Cl. D28—03
U.S. Cl. D86—10 C

FIG. 1 is a perspective view of an electrical manicuring apparatus showing my new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a bottom plan view; and

FIG. 7 is a top plan view.

I claim:

The ornamental design for an electrical manicuring apparatus, as shown.
